UNITED STATES PATENT OFFICE.

CLARENCE H. TAUBEL, OF RIVERSIDE, NEW JERSEY.

DESIGN FOR A STOCKING.

Application filed May 31, 1927. Serial No. 22,241. Term of patent 14 years.

To all whom it may concern:

Be it known that I, CLARENCE H. TAUBEL, a citizen of the United States, and a resident of Riverside, in the county of Burlington and State of New Jersey, have invented a new, original, and ornamental Design for a Stocking, of which the following description, in connection with the accompanying drawings, is a specification.

In the drawing:

The figure is a side elevation of a stocking embodying the design.

The design is not only an inverted clock, but is shadowed except at one vertical edge, so as to give a characteristically heavy right-hand edge with the rest of the clock much fainter and shadowed.

I claim:

The ornamental design for a stocking, as shown and described.

In testimony whereof, I have signed my name to this specification.

CLARENCE H. TAUBEL.
